CHILD'S OUTERWEAR ENSEMBLE

Willard H. Fischer, New York, N. Y., assignor to
Wee Moderns, Inc., New York, N. Y., a corpora-
tion of New York

Application April 20, 1951, Serial No. 222,023

3 Claims. (Cl. 2—70)

1

The present invention relates to a child's apparel, and, more particularly, to a child's outerwear ensemble, such as a coat and trouser combination of the type generally worn by a child or infant when outdoors.

Heretofore, in order to safely secure a child against a fall when in a vehicle, such as carriage or stroller, or when in a highchair, it has been customary to use a harness which fitted about the body and over the shoulders of the child and to which are attached clips that are secured to suitable fittings installed on the vehicle or on the highchair, or the like. The use of such baby harnesses has not been found completely satisfactory. They are generally of complicated arrangement and relatively involved and difficult to put on and take off; the putting on and taking off being necessary each time the child is dressed or undressed. They are not always completely safe for the reason that they permitted the child to twist and turn within the harness and sometimes out of it, and also, for that reason, frequently caused discomfort to the child.

It is a primary object of the present invention to provide a child's outerwear ensemble which is formed with its own safety attachment for a vehicle or high chair or the like and by which the child may be directly secured in such baby vehicle or highchair with maximum safety, thus eliminating the necessity for the use of any separate harness outfit and their putting on and removal each time the child is dressed or undressed.

It is another object of the present invention to provide a child's outerwear ensemble of the character described which will afford the child a maximum of comfort when in use and will not materially interfere with its comfort when not in use.

It is also an object of the present invention to provide a child's outerwear ensemble of the character described which may be used for the safety of the child with least trouble and inconvenience to the child's attendant.

It is a further object of the present invention to provide a child's outerwear ensemble of the character described the safety feature of which may be utilized with the individual members of the ensemble, separately, as well as in their assembled state, with equal safety, comfort and convenience both for child and attendant.

It is a still further object of the present invention to provide a child's outerwear ensemble having safety features which are of simple construction, simple and easy to use, are strong and durable and highly effective for their purpose, and which are relatively economical to provide with but little added cost to the cost of the garment ensemble, generally.

The foregoing and other advantages and superiorities of the child's outerwear ensemble of

the present invention will become more readily apparent to those skilled in the art from the embodiment thereof shown in the accompanying drawing and from the description following. It is to be understood, however, that such embodiment is shown by way of illustration only, to make the principles and practice of the invention more readily comprehensible, and without any intent of limiting the invention to the specific details therein shown.

2
In the drawings:

Fig. 1 is a front perspective view of the child's outerwear ensemble of the present invention, shown with the coat open, partly broken away and partly in section, and as used in combination with the safety belt; and

Fig. 2 is a front perspective view of the coat only, shown open and partly broken away and in use with the safety belt of the present invention.

Referring more specifically to the accompanying drawing, the embodiment of the child's outerwear ensemble illustrated is shown to comprise a coat member, generally designated as 10, and a trouser member, generally designated as 11. The coat member 10 may be of any desired length, such as the jacket length illustrated, and of any conventional style, fabric and construction generally used for children's coats or jackets. The trousers or leggings 11 may likewise be of any desired length, style, fabric and construction conventionally used for the purpose.

The coat or jacket may include a back section 12, a pair of front sections 13 secured to the back section 12 at its side edges, as at 14, sleeves 15, and a collar 16, all of which may be lined with a lining 17 or interlined or unlined, as may be desired. The front sections 13 may be provided with cooperating fastening means at their side edges, such as the button and button hole type, as illustrated by the button holes 18, or slide fasteners, or the like.

The back section 12 of the coat 10 may be provided at approximately the waistline of the garment and adjacent each of its side edges, near the connecting seams 14, with a vertically disposed slot 20 passing through the entire thickness of the garment, including lining and interlining, if any, from the inside to the outside of the garment; which slots 20 may have their edges finished, as by buttonhole stitching or other means to give them proper strength and appearance.

The trouser member 11 may comprise a body receiving portion 22 which extends upwardly at least to cover the waistline, and trouser leg portions 23; the body portion 22 having a back section 24 and a front section 25 secured to the back section and which may be formed of one or more fabric sections or gores. The back section 24 of the trousers 11 is likewise provided at ap-

proximately the waistline of the garment, with a pair of vertically disposed slots 26 extending therethrough from the inside to the outside, one adjacent each side edge of the back section 24. The slots 26 may likewise be formed with their edges finished, as by buttonhole stitching, for reinforcement and proper appearance. Preferably, the distance between the slots 26 may be slightly less than the distance between the slots 20 of the coat 10.

The ensemble of the present invention includes a band or belt of webbing or other suitable material 30 of a width adapted to pass through the slots 20 and 26 and of a length greater than the distance between the slots 20 of the jacket 10. The band 30 which may preferably be of wholly or partly longitudinally elastic material, if desired, may have secured thereto, at each of its ends, as by loops 31 formed at such ends, a metallic ring 32 through which is slidably passed an adjustably buckled strap 34 which slidably engages a clip 35 as by passing through the loop or eye 35 formed at one end thereof. It will be apparent, of course, that the clips 35 may be secured directly to the belt 30, if desired, or may be secured thereto by any other practical and convenient means.

In use with the ensemble, the belt 30 may be passed through the slots 26 of the trousers 11 from the inside to the exterior thereof, so that the ends of the belt 30 project outwardly from the trousers 11. After the trousers are placed on the child, the coat may be placed on the child and the strap ends then passed through the slots 20.

When a child is thus dressed with this ensemble, it will be apparent that it may be placed in any position in or out of a baby vehicle or highchair without danger or discomfort, or it may be secured in the vehicle or highchair for safety, with great speed and convenience, with a minimum of interference with the child's movements, with a minimum of trouble to the child's attendant, and without any possibility or chance of the child slipping out as it might from the harness now conventionally used, because such slipping out could be accomplished only with the removal of the ensemble.

It will be apparent, also, that the child may use either the trousers or the coat, one independently of the other, in association with the safety strap 30, as may be desired, in accordance with any change of temperature that might require the removal of one or the other, as when a child is brought into the house for feeding, for instance, when the jacket may be removed and then replaced with a minimum of trouble.

This completes the description of the child's outerwear ensemble of the present invention and the manner of its use. It will be readily apparent that numerous variations and modifications may be made therein, in accordance with the principles of the invention hereinabove described and without the use of any inventive ingenuity. I desire, therefore, to be protected for any and all such variations and modifications that may be made within the spirit of the present invention and the scope of the claims hereto appended.

What I claim is:

1. A child's outerwear ensemble of the character described comprising, in combination, a coat having a waistline covering portion, trousers having a waistline covering portion, said

jacket including a back section and front sections secured to the side edges of said back section and having means at their facing edges for separably securing one to the other, said jacket having spaced, vertical slits formed in its back section at approximately the waistline thereof, said trousers having a back section and a front section connected thereto, said trousers having vertical slits formed in the back section thereof at approximately the waistline thereof, said coat and trouser slits arranged to be in horizontal register when worn on the body and a belt passed from the inside of said trousers through the slits thereof and through the slits of said coat with its free ends extending outwardly of said coat, said belt having a clip secured at each end thereof.

2. A child's outerwear ensemble of the character described comprising, in combination, a coat having a waistline covering portion; trousers having a waistline covering portion, said coat including a back section and front sections secured to said back section at its side edges and means for separably securing the contiguous edges of said front section to one another, said coat having vertical slits formed adjacent each side edge of its back section at approximately the waistline thereof, said trousers having a back section and a front section connected thereto, said trousers having vertical slits formed therein adjacent the side edges of the back section thereof at approximately the waistline, and a belt passed from the inside of said trousers through the slits thereof and through the slits of said coat, with the free ends of said belt extending outwardly of said coat, said belt having a fastening clip secured at each end thereof.

3. A child's outerwear ensemble of the character described comprising, in combination, a coat having a waistline covering portion; trousers having a waistline covering portion, said coat including a back section and front sections secured to said back section, and means for separably securing the contiguous edges of said front section to one another, said coat having vertical slits formed therein adjacent each side edge of its back section at approximately the waistline thereof, said trousers having a back section and a front section connected thereto, said trousers having vertical slits formed therein adjacent the side edges of the back section thereof at approximately the waistline, the distance between said trouser slits being less than the distance between said coat slits; and a belt passed from the inside of said trousers through the slits thereof and through the slits of said coat with its free ends extending outwardly of said coat, said belt having a fastening clip secured at each end thereof.

WILLARD H. FISCHER.
